his Attorney

UNITED STATES PATENT OFFICE.

CHARLES H. COLE, OF BROOKLYN, NEW YORK.

POURING-LADLE.

1,238,108.

Specification of Letters Patent. Patented Aug. 28, 1917.

Application filed September 30, 1916. Serial No. 123,006.

To all whom it may concern:

Be it known that I, CHARLES H. COLE, a citizen of the United States, residing at the city of New York, borough of Brooklyn, 5 Kings county, in the State of New York, have invented certain new and useful Improvements in Pouring-Ladles, of which the following is a full, clear, and exact specification.

10 This invention relates to pouring ladles for use in pouring molten metal into molds and has for its object to provide a ladle of this character adapted to pour the molten metal into a plurality of molds at one 15 operation.

Further the invention has for its object to provide a ladle of this type with means for insuring the pouring of equal quantities of metal into each of the several molds.

20 Further the invention has for its object to provide a ladle having a distributing chamber with which the pouring members communicate whereby the molten metal within the chamber will be evenly distributed with respect to the several pouring 25 members.

Further the invention has for its object to provide means for varying the rate of flow of the metal to be poured therefrom.

30 Other objects will in part be obvious and in part be pointed out hereinafter.

To the attainment of the aforesaid objects and ends, my invention consists in the novel details of construction, and in the 35 combination, connection and arrangement of parts hereinafter more fully described and then pointed out in the claims.

In the accompanying drawing showing an 40 illustrative embodiment of the invention—

Figure 1 is a top view of the ladle;

Fig. 2 is an end elevational view thereof, and

Fig. 3 is a sectional view taken on the line 3—3 of Fig. 1.

45 Referring to the drawing the ladle comprises a receptacle 10 having a forwardly extending portion 10' provided with a front wall 11 having a plurality of pouring openings 12 extending therethrough and spaced

50 from the upper edge thereof. Projecting rearwardly from the upper edge of the front wall 11, and positioned above the openings 12, is a cover 13 which extends over the front portion of the receptacle 10 and has its rear edge spaced from the rear wall of the receptacle 10 a distance

sufficient to provide an opening to permit the molten metal to flow freely into the receptacle 10 when the ladle is dipped into the mass of molten metal prior to the pouring operation. A skimming member 14 extends downwardly from the cover 13 into the receptacle 10 in rear of the forwardly extending portion 10' and terminates a short distance from the bottom thereof for 60 the purpose of preventing the dross or scum, which may form on the surface of the molten metal, from passing out of the ladle and into the mold. The member 14 also serves to form a chamber 14' in the 65 forwardly extending portion 10' of the receptacle 10 within which the molten metal will be evenly distributed thus insuring an equal flow of the metal through the several pouring openings 12. At the rear of the 70 receptacle 10 there is provided a threaded boss 15 adapted to receive the threaded end of a handle 16 of any suitable size and form. A plate 17, detachably secured to the front wall 11 of the receptacle 10 by 75 screws 18 or the like, carries pouring nozzles 19 which, when the plate is in position, register with the openings 12 in the front wall 11. A plurality of these plates 17 are provided carrying nozzles 19 of different sizes whereby any desired one of the plates may be attached to the receptacle depending upon the size of the molds which are to be filled, it being understood that the openings 12 in the front wall 11 are of a size 80 corresponding to the largest sized nozzles 85 which are used.

In operation the plate 17 carrying the nozzles 19 of the desired size is secured to the receptacle by the screws 18. The ladle is then dipped into the mass of molten metal, being held by the handle 16, whereby the receptacle 10 is filled. The ladle is thereupon tilted to permit the molten metal to be poured from the receptacle 10 through the nozzles 19 into the molds. During the pouring operation the skimming member 14 prevents any dross or scum, which may have formed upon the surface of the molten metal, from passing into the chamber 14' thereby insuring that no dross or scum will pass through the pouring nozzles 19 and into the molds. The pure molten metal will flow beneath the skimming member 14 into the chamber 14' within which it will be distributed evenly with respect to the pouring openings 12 thereby insuring an equal flow 90 95 100 105 110

of molten metal through the openings 12 and the registering nozzles 19 and into the molds.

Should it be desired to change the rate of flow of the molten metal from the receptacle 10 the plate 17 is removed and another plate 17 is secured in position, as above described, which other plate carries nozzles 19 of a size adapted to permit of the desired rate of flow 10 of the molten metal.

Having thus described my said invention, what I claim and desire to secure by Letters Patent is:

1. A ladle comprising a receptacle provided with a distributing chamber, said receptacle having a plurality of openings in one of its walls and in communication with said chamber, and pouring members registering with said openings, substantially as 20 specified.

2. A ladle comprising a receptacle provided with a forwardly extending distributing chamber, said chamber being provided with a straight front wall having a plurality 25 of openings extending therethrough, and pouring members registering with said openings, substantially as specified.

3. A ladle comprising a receptacle provided with a forwardly extending distributing chamber having its front wall lying in a plane forming an angle with the plane of the top of the receptacle, said front wall having a plurality of openings extending therethrough, and pouring members registering with said 35 openings, substantially as specified.

4. A pouring ladle comprising a receptacle having a front wall lying in a plane forming an angle with the plane of the top of the receptacle, a plurality of openings in said 40 front wall, a cover projecting rearwardly from said front wall and extending over a portion of said receptacle, a skimming member extending downwardly from said cover

and terminating above the bottom of said receptacle whereby a chamber is formed with 45 which said openings communicate, and pouring members registering with said openings, substantially as specified.

5. A pouring ladle comprising a receptacle provided with a forwardly extending portion having a front wall lying in a plane forming an angle with the plane of the top of the receptacle, said front wall having a plurality of openings extending therethrough, a cover projecting rearwardly from 50 said front wall and extending over a portion of said receptacle, a skimming member extending downwardly from said cover at the rear of said forwardly extending portion and terminating above the bottom thereof 55 to form a distributing chamber, and pouring members registering with said openings, substantially as specified.

6. A pouring ladle comprising a receptacle having a plurality of openings in one of its 60 walls, a plate provided with a plurality of pouring members, and means detachably securing said plate to said receptacle with said pouring members registering with said openings, substantially as specified. 70

7. A pouring ladle comprising a receptacle having a plurality of openings in one of its walls, a plate, a plurality of pouring members secured to said plate, and means detachably securing said plate to said wall, with 75 said pouring members registering with said openings, substantially as specified.

Signed at the city of New York, in the county and State of New York, this 13th day of September, one thousand nine hundred and sixteen. 80

CHARLES H. COLE.
